UNITED STATES PATENT OFFICE.

KATHERINE G. HEALEY, OF CAMBRIDGE, MASSACHUSETTS, ASSIGNOR TO NASHUA MANUFACTURING COMPANY, OF NASHUA, NEW HAMPSHIRE, A CORPORATION OF NEW HAMPSHIRE.

DESIGN FOR A BLANKET.

Application filed July 1, 1924. Serial No. 10,020. Term of patent 14 years.

To all whom it may concern:

Be it known that I, KATHERINE G. HEALEY, a citizen of the United States, residing at Cambridge, county of Middlesex, and State of Massachusetts, have invented a new, original, and ornamental Design for Blankets, of which the following is a specification, reference being had to the accompanying drawing, forming a part thereof.

The figure is a plan view of a portion of a blanket showing my new design.

I claim:

The ornamental design for a blanket as shown.

Dated June 27, 1924.

KATHERINE G. HEALEY.
